(**) Term: **14 Years**

(57) **CLAIM**

(21) Appl. No.: **29/244,066**

The ornamental design for a non-hollow point shaped overcap, as shown and described.

(22) Filed: **Dec. 5, 2005**

DESCRIPTION

(51) **LOC (8) Cl. 09-07**

FIG. 1 shows a perspective view of the present invention.

(52) **U.S. Cl. D9/445; D9/454**

FIG. 2 shows a side view of the present invention.

(58) **Field of Classification Search** D9/686,

FIG. 3 shows a top view of the present invention; and,

D9/682, 529, 448, 447, 445, 444, 443, 440,

D9/435, 434; 222/182, 153.1; 220/915

FIG. 4 shows a side view of the present invention.

See application file for complete search history.

The broken lines in the drawings are for illustrative purposes only and form no part of the claimed design.
